UNITED STATES PATENT OFFICE.

PINDAR F. COOLEY, OF PITTSFIELD, MASSACHUSETTS.

IMPROVEMENT IN DREDGING-BOXES.

Specification forming part of Letters Patent No. 131,744, dated October 1, 1872.

To all whom it may concern:

Be it known that I, PINDAR F. COOLEY, of the town of Pittsfield, State of Massachusetts, have invented a new and Improved Dredging Packing-Box; and I do hereby declare that the following is a description thereof, reference being had to the accompanying drawing, in which—

Figure 1 represents the box embodying the improvements in this invention, illustrating the same closed; Fig. 2 is the same, represented set for dredging; Fig. 3 represents the same set for removing the contents of the box in mass; Fig. 4 is a sectional elevation of the same; Fig. 5 is a vertical view of the interior cover; Fig. 6 is a vertical view of the slipping exterior cover; and Fig. 7 is a sectional elevation, illustrating a modified form of construction of the box.

The same letters of reference indicate like parts.

My invention relates to a dredging packing-box, intended to hold spices for commerce, in which it will serve the double purpose of a packing-box for manufacturers and storekeepers, and also a dredging-box for house and table purposes; and consists in a sheet-metal box, made at one end with a head, which will be in one part solid, in another part with perforations for dredging purposes, and in another part open, which head is fixed immovable to the body of the box. Over the said fixed and partly solid perforated and open head, is placed an exterior sliding cover, part of which is cut away, which sliding cover is secured to the head by a rivet, or has its rim clinched or run over to hold the same in place, and also renders it capable of being revolved in either direction so as to bring the opening in the said cover over—either the opening or the perforated part or solid part of the head, as may be required. The opposite end of the box is made open, and is provided with a flanged cover, into which end the contents are to be introduced.

In the drawing, A A represent the body of box, which is made of sheet metal. B is a fixed head, secured in a proper manner firmly

to the body A, as shown in Fig. 4. The said head has one portion cut out, as portion a, which forms an opening to the body of the box, as shown in Figs. 3, 4, and 5. Another portion of the said head is provided with perforations x x x, as shown in Figs. 2, 5, and 7, which is to act as a dredge or sifter, while the remaining portion, b, is left solid, as in Figs. 1, 4, 5 and 7, which is to close beneath the opening in the sliding cover. C is the sliding cover, provided with a rim, c, and made of a size to nicely fit over the end of the box, as shown in the several drawings. A part of the top of the said cover is cut out to provide it with the opening d, which is made in size to correspond with the several parts a, x x, and b, made with the head B. The said sliding cover is secured to the box and over the head B by the central pivot Z or by having its flange or rim C milled over a bead formed by the lapped joint of the head with the body, as C', in Fig. 7; either of which modes will effectually secure the said sliding cover and permit its being revolved or slid around in either direction; and preference is given to the former in Fig. 7, because of the facility and perfection of the parts when made by machinery. The opposite end of the box is provided with a rim cover, D, which is to close the said end when filled. In using this invention for a packing-box the sliding cover is to be so turned that the opening d will be made to pass and stand over the solid portion b in the fixed end-head B, as in Fig. 1; the contents of the box are then introduced through the open opposite end, (the cover D being removed;) and when filled the cover D is to be placed thereon, and the box will be labeled in the usual manner. When used for a dredge-box the sliding cover C is to be turned to bring the opening d to uncover the perforations x x x, as in Fig. 2; and when to be used to take from the contents of the box in mass by a spoon or pouring out, the said opening d, over the opening a, in the head B, as in Fig. 3.

While by this invention this box is made to be adapted to all the purposes of a packing-box, it also answers all the purposes of a tight

sealed box, dredge-box, and an open box, in which no portion is required to be removed when the box is to be used for any of the purposes it is adapted to.

Having described my invention, what I claim and desire to secure by Letters Patent, is—

In a packing and dredge box, the combination of the sliding cover C provided with the

opening d, with the body A, and fixed head B, made part solid as b, and perforated as x x, and open as a, when all are constructed and arranged substantially as and for the purposes set forth.

PINDAR F. COOLEY.
